US00D755827S

(12) **United States Design Patent**
Anzures et al.

(10) **Patent No.:** US D755,827 S
(45) **Date of Patent:** ** May 10, 2016

(54) **DISPLAY SCREEN OR PORTION THEREOF
WITH GRAPHICAL USER INTERFACE**

(71) Applicant: **Apple Inc.**, Cupertino, CA (US)
(72) Inventors: **Freddy Anzures**, San Francisco, CA (US); **Greg Apodaca**, Mountain View, CA (US); **Ismael Basso**, San Francisco, CA (US); **Imran Chaudhri**, San Francisco, CA (US); **Jonathan Dascola**, San Francisco, CA (US); **Christopher Foss**, San Francisco, CA (US); **David C. Graham**, Campbell, CA (US); **Jonathan P. Ive**, San Francisco, CA (US); **Matthew Dean Rohrbach**, San Francisco, CA (US); **Brian Andrew Schmitt**, San Francisco, CA (US); **Christopher Daryl Soli**, Mountain View, CA (US); **Christopher Wilson**, San Francisco, CA (US)

(73) Assignee: **Apple Inc.**, Cupertino, CA (US)

(**) Term: **15 Years**

(21) Appl. No.: **29/540,698**

(22) Filed: **Sep. 26, 2015**

Related U.S. Application Data

(63) Continuation of application No. 29/537,751, filed on Aug. 28, 2015, which is a continuation of application No. 29/457,338, filed on Jun. 9, 2013, now Pat. No. Des. 737,833.

(57) **CLAIM**

The ornamental design for a display screen or portion thereof with graphical user interface, as shown and described.

DESCRIPTION

The FIGURE is a front view of a display screen or portion thereof with graphical user interface showing our new design. The outermost broken lines in the FIGURE show a display screen or portion thereof, and form no part of the claimed design. The other broken lines in the FIGURE show portions of the graphical user interface that form no part of the claimed design.
